William S. Tandler and Ferdinand A. De Weiss,
New York, N. Y., assignors to Continental Motors Corporation, Muskegon, Mich., a corporation of Virginia

Application February 6, 1945, Serial No. 117,779

Term of patent 14 years

(Cl. D55—1)

To all whom it may concern:

Be it known that we, William Stephen Tandler, a citizen of the United States of America, residing at 182 East End Avenue, New York city, in the county of New York and State of New York, and Ferdinand A. de Weiss, a citizen of Hungary (born in Austria) residing at New York city, in the county of New York and State of New York, have invented a new, original, and ornamental Design for a Portable Engine Power Unit Housing, of which the following is a specification, reference being had to the accompanying drawing, forming part thereof, in which:

Fig. 1 is a perspective view showing the top, front and one side of a portable engine power unit housing embodying our new design,

Fig. 2 is a top plan view thereof on a slightly reduced scale,

Fig. 3 is an elevational view of the end opposite to that shown in Fig. 1, on a similarly reduced scale, and

Fig. 4 is a rear elevational view thereof, also on a slightly reduced scale.

We claim:

The ornamental design for a portable engine power unit housing, as shown.

WILLIAM S. TANDLER.
FERDINAND A. DE WEISS.
